UNITED STATES PATENT OFFICE.

RICHARD JENTZSCH, OF CHICAGO, ILLINOIS.

SELF-RETAINING UTERINE-TUBE.

1,039,061.

Specification of Letters Patent. Patented Sept. 17, 1912.

Application filed February 8, 1911. Serial No. 607,229.

To all whom it may concern:

Be it known that I, RICHARD JENTZSCH, a citizen of the United States, residing at Chicago, in the county of Cook and State of Illinois, have invented new and useful Improvements in Self-Retaining Uterine-Tubes, of which the following is a specification.

The invention relates to a uterine tube, and more particularly to the class of self-retaining uterine tubes or supports.

The primary object of the invention is the provision of a tube in which a uterus may continuously drain thus permitting effete and noxious matters to continually pass out of the womb, without discomfort to the user, thereby assuring a healthy condition to the organ.

Another object of the invention is the provision of a tube of this character, in which the periodical menstruation flow of a womb will not be interfered with, or in any manner impeded, and that will correct any deviation therein, giving to the uterus and its appendages a perfect drainage, and allowing all broken down or diseased tissues to freely pass out of the womb, and also other noxious matters, thereby leaving the womb in a strong, clean and healthy condition.

A further object of the invention is the provision of a tube of this character which may be readily and easily inserted in the uterus, for retention therein, and that will not irritate the membrane or walls thereof, the tube being simple of construction, indestructible, light, reliable and efficient in operation, and inexpensive in manufacture.

With these and other objects in view, the invention consists in the construction, combination and arrangement of parts, as will be hereinafter more fully described, illustrated in the accompanying drawings, and pointed out in the claims hereunto appended.

In the drawings: Figure 1 is a sectional view of a vagina, showing the invention applied thereto in the uterus. Fig. 2 is a perspective view of the tube removed from the uterus. Fig. 3 is a side elevation thereof, when spread for its self retention in a uterus. Fig. 4 is an end view of the same. Fig. 5 is an opposite end view. Fig. 6 is a longitudinal sectional view.

Similar reference characters indicate corresponding parts throughout the several views of the drawings.

Referring to the drawings by numbers, 8

designates a vagina, and 9 the uterus having its cavity 10, in which is fitted the uterine tube, as will be hereinafter fully described. This uterine tube comprises a tubular body 60 or shell 11, constructed from a suitable non-irritating and indestructible material, preferably silver, or similar alloy, having a central bore 12 therein, tapering toward one end of said body or shell, the latter being also tapered toward one of its ends correspondingly to the taper of said bore 12 therein. The larger end of said body or shell 11 is provided with a flared annular flange 13, while the opposite smaller end is provided with 70 an outturned rounded annular flange 14, the flanges 13 and 14, respectively, being provided with concaved inner walls 15.

At diametrically opposite points of the body or shell 11, intermediate its ends, are 75 provided orifices 16, the same being intersected by longitudinally disposed slits 17 arranged directly opposite each other, and opening through the smaller end of said body or shell and severing said flange 14, to 80 provide bendable semi-circular shaped retaining legs or extensions 18, which are adapted to be outwardly deflected in diverging relation to each other for retaining the body or shell 11 within the uterus when positioned therein in a manner as will be hereinafter more fully described.

The mode of applying the device is as follows: The uterine tube is normally in the position as shown in Fig. 2 of the drawings, 90 so that the body or shell 11 can be easily inserted in the vagina for impinging it in the cavity 10 of the uterus 9, without tearing or otherwise injuring the lining of the womb. Thus the tube will be passed there- 95 in without causing pain to the patient. Any suitable instrument is employed for inserting the uterine tube, which latter is passed into the uterine cavity 10, so that the larger end of the body or shell 11 will lie in the 100 internal os of the uterus, whereupon the retaining legs or extensions 18 are separated from each other, so that the same will inwardly diverge, thereby flaring the smaller end of the body or shell 11, caus- 105 ing the flange 14 on the extremities of the legs or extensions 18 to impinge with the parallel walls of the uterus, above the internal os, so that on contraction of the external os to normal about the body or shell 11, the latter will be perfectly held in place

110 in the cavity in the uterus for the proper

drainage thereof, whereby allowing effete or noxious matters and also diseased or broken down tissues therein to freely pass out of the vagina, to render the same strong and in a healthy condition.

It will be obvious that menstruation will not be interfered with, and that the tube will be self retained within the uterus, without possibility of accidental displacement or the dropping thereof from the vagina.

From the foregoing description, taken in connection with the accompanying drawings, it is thought that the construction and operation of the invention will be readily understood without requiring a more extended explanation, and therefore the same has been omitted.

What is claimed is:

As an article of manufacture, a self retaining uterine tube comprising a tubiform

body having an end portion tapering outwardly from a point spaced from the intermediate portion of said tube, the said tapered end being provided at diametrically opposite points with slits and also with circular orifices at the inner ends of said slits to provide separable semicircular-shaped retaining legs adapted to be flared in diverging relation with respect to each other, a flared annular flange formed at the larger end of the tube and having a rounded edge, and outwardly rounded semi-annular flanges formed on the legs at the free edges thereof.

In testimony whereof I affix my signature in presence of two witnesses.

RICHARD JENTZSCH.
